UNITED STATES PATENT OFFICE.

THEODORE DOUGLAS, OF SCARBORO, NEW YORK.

RAILWAY-CAR-CONNECTING PLATFORM.

1,040,529.

Specification of Letters Patent.

Patented Oct. 8, 1912.

Application filed July 24, 1912. Serial No. 711,272.

To all whom it may concern:

Be it known that I, THEODORE DOUGLAS, a citizen of the United States, and resident of Scarboro, county of Westchester, 5 and State of New York, have made a new and useful Invention in Railway-Car-Connecting Platforms, of which the following is a specification.

My invention is directed primarily to appliances adapted for use on railway passenger-cars to provide a safe tread and continuous platform from one car to the adjoining car when the cars are coupled together and in motion; this platform, or 15 bridge, being so designed as to permit the cars to traverse any track curvature or rail inequalities ordinarily found on such roads and to automatically seek its own adjustment with reference to the car ends and its 20 connection between the cars, and to form a continuous and safe tread for the passengers crossing thereupon.

My invention will be fully understood by referring to the accompanying drawings, in 25 which,

Figure 1 is a plan view of the adjoining ends of two passenger cars showing the platform connecting them. Fig. 2 is a longitudinal section along the line X, X, and Fig. 30 3 is a cross section along the line y, y.

It often occurs on railway trains that passengers become injured in passing from one car to another as a result of stepping into the gap between the cars which at times becomes much enlarged owing to the inequalities of the road and to the curvature of the track. Thousands of accidents occur 35 annually from this cause and many of which prove fatal. My invention is designed to overcome this danger and menace to life 40 in affording the passenger, or railway employee, a safe tread in passing from one car to another.

On most rapid transit roads the employees 45 operating the doors of the cars are compelled to stand between the car ends and are often injured from their feet slipping in between the cars on the lurching of the cars, or from other causes, and this platform will afford 50 them a safe floor upon which to stand in the performance of their duties. I accomplish this by a combination of springs and a plate made of steel or of other suitable substance supported on the floor of the car 55 and in surface alinement with the floor. This plate projects out beyond the end of

the car and terminates in a smooth surface parallel to the cross section of the car. When two cars are coupled the plates contact on their outer edges and surface with 60 each other in alinement with the floor of the cars. The plates are held in contact position with each other by springs and are held in contact with the floor of the car by means of an opening in the car floor through 65 which a connecting circular boss passes to the under side of the floor and which is there attached to a plate of dissimilar size and form to the one above the floor. This opening in the floor is of such size as to permit 70 this vertical boss to move back and forth in line with the major axis of the car and also to move across that axis in following the inequalities of the car end movements.

Referring now to the drawings in detail 75 and first to Fig. 1, where a complete application of the invention is shown, C, C represent two car ends and 1, 1 the abutting plates, or platform. 2, 2 represent the oval openings in the floor of the cars and 3, 3 80 the plates beneath the cars connected to the plates 1, 1 by means of the bosses 4, 4. The plates 1, 1 are divided along the line 5. The springs 6, 6, 6, 6 are connected at their back ends to cast lugs 7, 7, 7, 7 of the under plates 85 3, 3, and at their opposite ends they are connected to the body of the car by the brackets 8, 8, 8, 8. These springs are in tension and have a tendency to extend the plate farther out beyond the end of the car thus 90 forcing the two plates into constant contact with each other along the line 5. The springs 9, 9 are connected at their front ends to the bosses 10, 10, of the under plate and at their opposite ends they are connected to 95 the body of the car by the brackets 11, 11.

12, 12, see Fig. 2, are double-headed keys passed through slots in the circular bosses 4, 4 and held permanently in their proper position by the metal shims 13, 13 having 100 their ends turned downward to prevent their dislodgment, there being used shims of such number and size as to fill the vacant space in the slots between the double-headed keys 12, 12 and the under plates 3, 3; they are 105 designed to secure the keys in place and to keep the under plates in contact with the floor of the car.

2, 2 represent the oval openings in the floor of the cars and show the longitudinal 110 motion permitted of the bosses 4, 4 which work in them.

- 14, 14 are downward extensions of the plate 1, 1 offering a broader surface for the vertical motion between the cars along the line 5.
- 5 2, 2, see Fig. 3, show the opening in the floor of the car, and indicate the amount of transverse motion permitted of the boss 4.
- 3 represents the under plate, 12 the double-headed key, and 13 the shims.
- 10 15, 15 are two downwardly extending lugs from the plate 3 holding the key 12 in a fixed position relative to the plate 3 and causing the plate 3 to follow the torsion movements of the plate 1.
- 15 8, 8 are brackets connecting the front ends of the springs 6, 6 to the body of the car.
- The operation of the device is as follows: When the cars are disconnected the springs 6, 6, 6, 6 pull the plates 1, 1, forcing them 20 outwardly beyond the ends of the car; on the coupling of the cars the two plates contact along the line 5 and are forced inward a distance corresponding to the end clearance of the cars and the springs 6, 6, 6, 6
- 25 are placed in greater tension thereby. After the cars are coupled and the train is in motion the unequal alinement of the car ends is followed and taken care of by the flexibility of the springs, the springs 6, 6, 6, 6
- 30 keeping the two plates in surface with each other, and the springs 9, 9 keeping the plates in alinement with the cars, though all of the springs interact to that end. Vertical motion is provided for along the line 5 and
- 35 extreme transverse movement may be taken up along the same line.
- I do not limit myself to the special details of construction shown as I believe that it is broadly new with me to provide a device 40 of this nature permitting of extensive longitudinal and transverse motion in the device itself with reference to the car. In the application of this device it may be placed below the floor of the car and the springs may
- 45 be attached in a suitable manner to the upper plate with the lower plate and its connections eliminated. In all other devices transverse motion is provided for along the line 5 and through rotation on a fixed center and in no other way, and my claims are 50 generic as to this feature.
- I do not limit myself to the use of my invention on railway trains as the same may be applied to other moving vehicles, and in 55 other ways.
- Having thus described my invention what I claim and desire to secure by Letters Patent of the United States is—
1. The combination of a rigid car platform at the end of a car, a floating auxiliary platform extending out beyond the end of the rigid platform, an opening in the rigid
- platform below the floating platform, a circular boss extending downward from the floating platform, as a part thereof, through 65 this opening in the rigid platform, and a plate of greater area than the opening in the rigid platform, means for rigidly connecting the plate on the under side of the opening to the floating platform, through 70 the boss member, in such a manner as to permit of a sliding motion of the floating platform, both longitudinal, circular and transverse, within the limits of the boss movements in the opening, and a plurality of 75 tension springs connected at one of their ends to the plate and at their opposite ends to the rigid platform, in such a manner as to permit of longitudinal, transverse and circular motions in the floating platform 80 when acted upon by a corresponding platform held in a floating position by corresponding springs on an adjoining car, and the said springs being so designed and adjusted as to keep the two platforms in contact, and yet to permit of extreme transverse and vertical movements along their contact faces, and when the two floating platforms are in contact to present a continuous tread or safety-bridge joining the 85 two cars, and when released from the influence of the adjoining platform and the movements of the car end, to return the floating platform to its normal position with reference to the rigid platform, substantially as described.
2. An appliance for use with moving vehicles constituting a platform, or bridge, connecting them and consisting of a plate attached to each vehicle and held in a position of contact with a corresponding plate on the adjoining vehicle by means of springs so arranged as to permit of longitudinal and transverse motions of the plates and circular motions without fixed centers, substantially as described.
3. An appliance for use on railway cars consisting of plates extending beyond the ends of the cars and which, when the cars are coupled, surface with each other and are held in their surfaced position by means of springs which permit longitudinal, transverse and circular movements of the plates to compensate the irregular motions of the ends of the cars and to constantly form a bridge, or platform, connecting between them over which the passengers may walk, substantially as described.
- In testimony whereof I affix my signature in presence of two witnesses.
- THEODORE DOUGLAS.
